CLAIM

The ornamental design for a pair of tool handles, as shown and described.

DESCRIPTION

FIG. 1 is a top end perspective view of a pair of tool handles showing our new design;
FIG. 2 is a bottom end perspective view thereof;
FIG. 3 is a back view thereof;
FIG. 4 is a side view thereof;
FIG. 5 is a top view thereof;
FIG. 6 is an opposite side view thereof;
FIG. 7 is a bottom view thereof; and
FIG. 8 is a front view thereof.

The broken lines are shown in the views for illustrative purposes only and form no part of the claimed design.

1 Claim, 3 Drawing Sheets
